SIGNAL DEVICE

Lloyd Rittenhouse, Honeoye Falls, N. Y., assignor
to The A. E. Rittenhouse Co., Inc., Honeoye
Falls, N. Y., a corporation of New York

Application October 5, 1938, Serial No. 233,357

2 Claims. (Cl. 177—7)

This invention relates to a signal device, of the general type employed to take the place of the conventional house door bell or other signal unit, consisting of electric striker operating mechanism in conjunction with a resonance chamber and vibratable plate or chime bar that is struck and gives the desired signal upon the closing of an electric circuit, and it has for its object to afford an economical and practical arrangement 10 designed to answer the requirements, and available as a low priced unit.

More particularly the invention has for its purpose to afford structure in which the resonance chamber and electric striker operating 15 mechanism are arranged in front of and mounted on a supporting plate that is attachable to a wall or other suitable surface.

Still an additional object of the invention is to provide a construction in which a resonance chamber is provided in a housing of light weight 20 metal stock and of consequent low cost, together with striker operating mechanism located in the housing, and both rigidly attached to a support which may be of a heavier metal than the housing, 25 and designed to hold all the parts in a stable, unitary relationship.

An additional purpose of the invention is to afford a construction that permits a quick and economical assembly of the several parts and results in a finished unit that is compact and 30 pleasing in appearance when arranged in operative position.

To these and other ends, the invention consists in the construction and arrangement of parts 35 that will appear clearly from the following description, when read in conjunction with the accompanying drawing, the novel features being pointed out in the claims following the specification.

40 In the drawing:

Fig. 1 is a front elevation of a signal device, partially in vertical section, constructed in accordance with one embodiment of the invention;

Fig. 2 is a side elevation, partly in section, and

45 Fig. 3 is a horizontal sectional view on the line 3—3 of Fig. 1 looking downwardly.

This application is a continuation in part of application Serial No. 175,296, filed November 18, 1937, which eventuated in Patent No. 2,147,498, 50 February 14, 1939 and has to do specifically with the relation of the supporting plate, resonance chamber housing, and electric striker operating means, and the construction by which these parts are united.

55 Referring more particularly to the drawing, in

which like reference numerals refer to the same parts, 1 designates the supporting plate having an opening 2 to receive a suitable fastening means by which it can be secured to a wall or other surface, the supporting plate 1 being of 5 sufficiently heavy metal stock to give the required rigidity and stability to the structure.

The supporting plate 1 preferably carries a chime bar or vibratable plate 3 which may be mounted thereon in any suitable way. In the 10 present arrangement, the supporting plate is provided near its ends with arms having offset portions 4 and 5 connected by vertical portions 6, and the chime bar 3 has openings 7 permitting it to be arranged on the portions 5 of the supporting arms as shown. It is to be understood that the chime bar may be otherwise attached to the support, and may be permanently positioned thereon if preferred instead of being removable, 15 the particular manner in which the chime bar 20 is mounted on the supporting plate forming no part of the invention herein claimed.

The resonance chamber is provided by a housing 8, which is secured to the supporting plate in a manner that will be described presently, 25 and may be formed of light weight metal such as tin plate or other suitable material. The housing 8 is closed at the bottom by the wall 9, and may be provided around its upper edge with the exterior band 10 which is preferably spot-welded to the housing 8 at a portion or portions 30 along the front edge thereof, while 11 designates an electromagnet or solenoid mounted within the housing 8 and provided with a striker 12 that is movable upwardly through the open top of the 35 resonance chamber to engage the chime bar 3 when the circuit is closed.

The housing 8 forming the resonance chamber and the electromagnet 11 are both secured to and carried by the supporting plate 1 in any suitable 40 and practical manner. To accomplish this, the electromagnet is carried by a bracket consisting of metal straps 16 and 14, the latter including an upstanding portion 15 by means of which the bracket is secured to the supporting plate 1.

According to one practical application of the invention, the supporting plate 1, band 10, and housing 8 may have struck therefrom the forwardly extending ears 17 which act as a positioning or centering means for the solenoid plate 50 or bracket portion 15, the latter being provided with cut-away portions or recesses 18 to accommodate said ears. With the parts located in this relationship, a spot-welding operation is effected through the supporting plate, band 10, housing 55

8, and bracket arm 15, as indicated at 19, and these parts are held together firmly and rigidly by the welds at these two points, which serve to secure the housing and solenoid bracket tightly 5 to the supporting plates and unite them rigidly thereto.

While I have disclosed an electric welded connection between these several parts, it will be understood that the resonance chamber housing 10 and solenoid bracket may be attached by riveting, soldering, or in any other suitable manner to the supporting plate, provided the parts are firmly attached thereto so as to afford a permanent and durable union. Binding posts 20 are 15 provided on the supporting plate 1, one of which is insulated therefrom and connected with the solenoid, and affording means for connecting with the electric circuit as usual the other side of the solenoid being grounded to the frame.

20 With the arrangement described, it is possible to utilize a very light weight metal for the resonance chamber housing, and thus effect a considerable saving as compared with structures where the housing must be made of sufficiently 25 heavy metal to support the chime bar and electric striker operating unit. Another advantage in making the resonance chamber housing of light weight metal is that it permits forming the housing on high-speed, automatic can-making 30 machines, which is not possible where heavy stock is required. By securing the solenoid bracket and housing to the supporting plate at the same point, it is possible to unite the three elements quickly 35 in one operation, as for instance where the several surfaces are spot-welded together.

While the invention has been described with reference to a particular embodiment, it is not confined to the details of construction herein dis-

closed, and this application as intended to cover any modifications or changes coming within the spirit of the improvements or the scope of the following claims.

I claim:

1. In a signal device, the combination with a vertically positionable supporting plate, of a vertically arranged housing located in front of the supporting plate and constituting a resonance chamber, said housing having the upper portion 10 of its rear wall fixedly attached to the central part of the supporting plate, the supporting plate extending laterally and upwardly beyond said housing, a chime bar mounted on the end portions of the supporting plate, electric striker operating mechanism located within the housing for actuating a striker upwardly to engage the chime bar, and a bracket for said striker operating mechanism, said bracket being positioned against the upper portion of the rear wall of the housing 15 and attached to the central lower part of the supporting plate.

2. In a signal device, the combination with a vertically positionable supporting plate, of a vertically arranged housing located in front of and 25 extending below the supporting plate and constituting a resonance chamber, a chime bar horizontally arranged above said resonance chamber, and electric striker operating mechanism located within the housing for actuating a striker to 30 engage said chime bar, a portion of the rear wall of said housing being secured to said supporting plate and the striker operating mechanism also being directly secured to said supporting plate whereby said supporting plate constitutes a major 35 supporting means for the striker operating mechanism.

LLOYD RITTENHOUSE.
